UNITED STATES PATENT OFFICE.

ADELINE M. WALKER, OF ELIZABETH, NEW JERSEY, AND FRANCES C. JACKSON, OF NEW YORK, N. Y.

DESIGN FOR A GARMENT-HANGER.

SPECIFICATION forming part of Design No. 28,449, dated April 5, 1898.

Application filed October 1, 1897. Serial No. 653,755. Term of patent 3½ years.

To all whom it may concern:

Be it known that we, ADELINE M. WALKER, a citizen of the United States, and a resident of the city of Elizabeth, county of Union, and State of New Jersey, and FRANCES C. JACKSON, a citizen of the United States, and a resident of the city, county, and State of New York, have invented and produced a new and original Design for a Garment-Hanger, of which the following is a specification.

We have illustrated our garment-hanger in the accompanying drawing.

The figure is a plan view of our device with the legs of the pins unclasped.

5 The garment-hanger is a substantially flat device formed of a single piece of wire and clasps attached to its sides as follows: A piece of suitable material with sharpened ends is bent at the middle to form the circular loop A, and at the bottom of the loop, at a', the free ends of the wire are twisted to form the shank b', extending downward, but in the same plane with the loop A, and forming the back or shank of the pins B and B.

At b² and b² the end wires are bent upward, ²⁵ but in opposite directions, as shown in the drawing, forming the prongs or hooks b³ and b³ with the points b⁴ and b⁴. c and c are clasps attached to the sides of the loop A.

As shown in the drawing, the leading or ³⁰ material feature of our design consists of a circular body or loop and a twisted shank at the bottom of said loop, said shank ending in hooks or pins placed side by side.

Having fully described our new and original design, what we claim, and desire to secure by Letters Patent, is—

The design for a garment-hanger herein substantially as shown and described.

Signed at New York, in the county of New ⁴⁰ York and State of New York, this 25th day of September, A. D. 1897.

ADELINE M. WALKER.
FRANCES C. JACKSON.
